(57) **CLAIM**

The ornamental design for a pet bed furniture, as shown and described.

DESCRIPTION

FIG. 1 is an isometric view of a first embodiment of the design formed as an elongated version of the design with the door open;

FIG. 2 is a view of the front of the elongated version of FIG. 1 with the door open;

FIG. 3 is a view of the back of the elongated version of FIG. 1;

FIG. 4 is a view of one side of the elongated version of FIG. 1;

FIG. 5 is a view of the other side of the elongated version of FIG. 1;

FIG. 6 is a view of the top of the elongated version of FIG. 1;

FIG. 7 is a view of the bottom of the elongated version of FIG. 1;

FIG. 8 is an isometric view of the elongated version of FIG. 1 with the door closed;

FIG. 9 is an isometric view of a second embodiment of the design formed as a shortened version with the door open;

FIG. 10 is a view of the front of FIG. 9;

FIG. 11 is a view of the back of FIG. 9;

FIG. 12 is a view of one side of FIG. 9;

FIG. 13 is a view of the other side of FIG. 9;

FIG. 14 is a view of the top of FIG. 9;

FIG. 15 is a view of the bottom of FIG. 9;

FIG. 16 is an isometric view of FIG. 9 with the door closed; and,

FIG. 17 is a view of the back of a third embodiment of FIGS. 8 and 16, with the back door open and showing the back of the front door shown in FIGS. 8 and 16.

The features shown in broken lines depict environmental subject matter and form no part of the claimed invention.

1 Claim, 13 Drawing Sheets
